COMBINATION CHIN REST AND SHOULDER PAD

Filed June 27, 1928

UNITED STATES PATENT OFFICE

FREDERICK GOSPARLIN, OF CHICAGO, ILLINOIS

COMBINATION CHIN REST AND SHOULDER PAD

Application filed June 27, 1928. Serial No. 288,697.

This invention relates to a combination chin rest and shoulder pad for attachment to a violin and has for its primary object to provide in a manner as hereinafter set forth, a device of the class above mentioned, wherein the chin rest and shoulder pad are formed from molds taken directly from the jaw and collar bone respectively.

A further object of the invention is to provide a chin rest and shoulder pad as aforesaid, including as a part thereof, means for adjustably clamping the chin rest and shoulder pad portions together, and for further clamping the same to a violin through the medium of the hole which is formed in violins for accommodation of the tail piece button.

Other objects and advantages of the invention will be apparent during the course of the following description.

In the drawings in which like numerals are employed to designate like parts throughout the same,

Figure 1 is a fragmentary plan view of a violin showing an embodiment of my invention secured thereto,

Figure 2 is an end elevation of the same,

Figure 3 is a section taken on line 3—3 of Figure 1,

Figure 4 is a section taken on line 4—4 of Figure 3,

Figure 5 is a section taken on line 5—5 of Figure 3, showing the shoulder pad in fragmentary plan,

Figure 6 is a perspective detail view of the chin rest.

In the drawings wherein for the purpose of illustration is shown an embodiment of my invention, the numeral 1 designates a violin, including the usual block 2 at one end thereof, said end and block being formed with a bore 3 for the accommodation of the usual tail piece button, not shown. I prefer to use the bore 3 for securing my attachment in position, and for this purpose a clamp nut 4 is substituted for the customary tail piece button.

The chin rest 5 according to my invention, consists of a vertical portion 6 and an angularly offset, horizontally extending portion 7. The vertically extending portion 6 is formed with a transverse groove 8, which divides the

portion 6 into a pair of legs 9 for seating on the upper face of the violin. The groove 8 is adapted to receive therethrough the tail piece of the violin not shown. The horizontally extending portion 7 is formed with tapered ends 10 and 11 respectively and is provided in the face thereof with a diagonally extending depression 12. That portion of the chin rest 5 which extends between the depression 12 and the end 11 is elevated above the remaining surface of the chin rest and forms a raised roll 13 substantially triangular in contour. The chin rest 5 is formed from a mold taken directly from the human jaw, and in applied position, the depression 12 receives therein the jaw bone of the user and the roll 13 fits within the hollow behind and underneath the jaw bone.

The shoulder pad 14 is of elongated formation and has its rearward edge 15 slightly convexed and its forward edge 16 slightly concaved. One end 17 of the shoulder pad 14 is of substantially greater thickness than the opposite end 18, and the rearward edge 15 is of substantially greater thickness than the forward edge 16. The lower surface 19 of the shoulder pad 14 is formed in a manner to conform to the configuration of the human collar bone. The shoulder pad 14 is of slightly less length than the length of the chin rest 5 and in assembled relation the end 17 of the shoulder pad 14 projects outwardly from the end 11 of the chin rest 5.

Secured to the upper face of the shoulder pad 14, by means of suitable holdfast devices 20, is a clamping member 21, which is formed with a reduced extension 22 which is bent upwardly and returned parallel to the horizontal plane of the main portion of the member 21 and spaced therefrom. Adapted for engagement with the extension 22 is a pair of spaced bars designated by the numerals 23 and 24 respectively. In assembled relation the bar 23 seats beneath the extension 22 and the bar 24 seats above said extension. The relative thickness between the bars 23 and the space between the extension 22 and member 21, and the relative thickness of the extension 22 to the space between the bars 23 and 24 provides for a snug fit when the several

members are in assembled relation. The rearward edges of the bars 23 and 24 are in alignment with the rear edge of the violin, and extending rearwardly from the bar 24 is a pair of arms 25 which terminate in vertical portions 26, which extend in parallel relation to the end of the violin and are spaced therefrom. The portions 26 are formed with external left hand threads for a purpose to be hereinafter disclosed.

10 The rearward faces of the legs 9 of the chin rest are formed with a pair of bores 27, into which a pair of arms 28 are threaded. The arms 28 terminate in vertically extending portions 29, which are disposed in opposing relation to the portions 26, and are formed with external right-hand threads. The portions 29 and 26 are connected together by means of a pair of internally threaded cylindrical couplings 30.

15 For securing the chin rest and shoulder pad to the violin, I provide a pin 31 which is adapted to be inserted into the bore 3 of the block 2. The inner end of the pin 31 is formed with a longitudinal slot 32, between the opposing walls of which is pivoted a tilt key 33. The point of pivotal connection 34 for the tilt key 33 is located between the transverse median of the tilt key and one end 20 thereof. Due to its increased length, the end 35 of the tilt key 33 is heavier than the end 36 so that the key 33 will normally swing about its pivot to assume a vertical position. Preferably the end 35 is thicker than the end 36 to further increase the weight of the end 35. The pin 31 is formed with a rearwardly extending, reduced, externally threaded extension 37, which projects rearwardly from the end of the violin when the tilt key 33 is positioned to lie flat against the inner face 40 of the block 2.

25 Connecting the couplings 30 is a concaved plate 38, each end of which is formed with a pair of curved fingers 39 the inner surfaces of which conform in contour to the outer surfaces of the couplings 30. The plate 38 is formed with a centrally disposed perforation 40 to receive therethrough a collar 41 formed on the inner end of the clamp nut 4. The collar 41 is formed with internal threads for engagement with the external threads of the extension 37 of the pin 31. Rearwardly of the collar 41, the clamp 4 is formed with an annular shoulder 42, the inner face of which abuts against the outer face of the plate 38.

30 When the clamp nut 4 is rotated to tighten the connection between the collar 41 and the extension 37, the plate 38 is drawn towards the end of the violin by the action of the shoulder 42 on the plate and of the tilt key 33 on the inner end of the block 2. Preferably a groove or indentation 43 is formed in the inner face of the block 2 to assist in holding the tilt key 33 against rotation when the clamp nut 4 is rotated to tighten the con-

nection. The extreme end 44 of the clamp nut 4 is enlarged to equal the diameter of the shoulder 42, thereby providing a neck portion 45 of reduced circumference.

35 To assemble my improved chin rest and shoulder pad and to secure the same to a violin, the arms 25 and 28 are respectively connected with the shoulder pad 14 and chin rest 5. The portions 26 and 29 of the arms 25 and 28 are loosely connected together by 40 means of the couplings 30. The plate 38 is then positioned relative to the couplings 30, the collar 41 of the clamp nut 4 is inserted through the perforations 40 and loosely threaded onto the extension 37 of the pin 31. The smaller end 36 of the tilt key 33 is then positioned within the slot 32 and the pin 31 is inserted into the bore 3. As soon as the end 36 clears the wall of the bore 3, the abnormal weight of the end 35 of the tilt key 45 33 automatically swings the tilt key to a vertical position. The pin is then withdrawn until the tilt key 33 lies flat against the inner surface of the block 2 and the clamp nut 4 is rotated to tighten the connection between 50 the collar 41 and the extension 37. After the attachment has thus been secured to the violin, the chin rest 5 and shoulder pad 14 respectively may be drawn into frictional contact with the upper and lower surfaces 55 of the violin by rotating the couplings 30. The couplings 30 are provided with tool receiving apertures 46 for this purpose.

60 It is to be understood that the form of my invention herewith shown and described is 100 to be taken as the preferred example of the same and that various changes in the size, shape and arrangement of parts may be resorted to without departing from the spirit of the invention or the scope of the appended 105 claim.

What I claim is:

1. In a chin rest and shoulder pad for a violin, a chin supporting member formed with tapered ends and having its upper surface 110 formed with a diagonally extending elongated depression, a triangular raised portion formed on one of said ends and abutting said depression, a member having a curved contour to conform with the contour of the collar bone, means for adjustably clamping said members together, and means coacting with said clamping means for securing the members to a violin, said securing means including a pin for insertion through the hole 115 formed in the violin for the accommodation of the tail piece button and further including means carried by the inner end of the pin for locking the latter in position.

2. In a chin rest and shoulder pad for a 125 violin, a chin supporting member formed with tapered ends and having its upper surface formed with a diagonally extending elongated depression, a triangular raised portion formed on one of said ends and abutting 130

said depression, a member having a curved contour to conform with the contour of the collar bone, means for adjustably clamping said members together, means coacting with 5 said clamping means for securing the members to a violin, said securing means including a pin for insertion through the hole formed in the violin for the accommodation of the tail piece button, and a tilt key pivot- 10 ally carried on the inner end of said pin.

3. In combination with a chin rest and shoulder pad, means for adjustably securing the chin rest and shoulder pad together, and means coacting with the securing means for 15 clamping the chin rest and shoulder pad to a violin, said clamping means including a pin for insertion in the hole for the tail piece button.

4. In combination with a chin rest and 20 shoulder pad, means for adjustably securing the chin rest and shoulder pad together, and means coacting with the securing means for clamping the chin rest and shoulder pad to a violin, said clamping means including a pin 25 for insertion in the hole for the tail piece button, said securing means including a pair of downwardly depending arms carried by the chin rest, and a pair of arms carried by the shoulder pad in opposed relation to the 30 chin rest arms.

5. In combination with a chin rest and shoulder pad, means for adjustably securing the chin rest and shoulder pad together, and means coacting with the securing means for 35 clamping the chin rest and shoulder pad to a violin, said clamping means including a pin for insertion in the hole for the tail piece button, said securing means including a pair of downwardly depending arms carried by 40 the chin rest, and a pair of arms carried by the shoulder pad in opposed relation to the chin rest arms, said pairs of arms being oppositely, externally threaded, and an internally threaded coupling for connecting ad- 45 jacent arms of opposite pairs.

6. In combination with a chin rest and shoulder pad, couplings for adjustably securing the chin rest and shoulder pad together, and means coacting with the couplings for 50 clamping the chin rest and shoulder pad to a violin, said clamping means including a pin for insertion in the hole for the tail piece button, a member for engagement with said 55 couplings, and a clamp nut for engagement with said member and pin to maintain said member in clamping engagement with the couplings and to provide a rigid connection between said member and pin.

60 7. In combination with a chin rest for a violin, a clamp nut for engagement with the hole formed in the violin to accommodate the tail piece button, means for connecting the chin rest and clamp nut, a pin having 65 its outer end in engagement with the clamp

nut, and a tilt key secured to the inner end of said pin.

8. In a chin rest and shoulder pad for a violin, a chin supporting member having its upper surface formed with an upwardly extending convexed portion and a substantially flat portion extending in a plane at substantially a right angle to the direction of extension of the convexed portion, said upper surface being further formed with a diagonally extending depression into which said portions merge. 70 75

9. In a chin rest and shoulder pad for a violin, a chin supporting member having its upper surface formed with an upwardly extending convexed portion and a substantially flat portion extending in a plane at substantially a right angle to the direction of extension of the convexed portion, said upper surface being further formed with a diagonally extending depression into which said portions merge, said convexed portion being raised above the plane of the substantially flat portion and further being substantially triangular in contour. 80 85 90

In testimony whereof, I affix my signature hereto.

FREDERICK GOSPARLIN.
